STARTING DEVICE FOR SPACE HEATERS OF THE PULSE JET TYPE

Filed Oct. 12, 1950

FIG. 7.

UNITED STATES PATENT OFFICE

2,684,712

STARTING DEVICE FOR SPACE HEATERS
OF THE PULSE JET TYPE

Wunibald I. E. Kamm, Willy F. Krautter, and
Kurt Staiger, Dayton, Ohio; said Kamm and
said Krautter assigns to the United States of
America as represented by the Secretary of the
Air Force

Application October 12, 1950, Serial No. 189,876

3 Claims. (Cl. 158—28)

(Granted under Title 35, U. S. Code (1952),
sec. 266)

1

The invention described herein may be manufactured and used by or for the United States Government for governmental purposes without payment to us of any royalty thereon.

This invention relates to starters for space heaters of the pulse jet type. It is an improvement on the subject matter described in our application Serial No. 144,556, filed February 16, 1950, entitled "Gas Starters for Resonant Pulse Jet Burners" Patent No. 2,653,654 dated September 29, 1953.

Briefly stated the invention is a starting system of the type in which the pulse jet combustion chamber of a pulse-jet resonant type of space heater is started into operation by pre-heating one spot in the wall of the combustion chamber to incandescence or at least to a temperature in which a premixed charge of fuel and air introduced into the combustion chamber will be fired, thereby setting the heater into resonant operation. The present improvement, resides in the structure of the means provided to introduce a premixed charge of fuel and air into the combustion chamber after the hot spot has been created. Additional means are provided to render the just mentioned fuel-air charge introducing means inoperative after the starting of the pulse type heater.

One of the objects of the invention is therefore the provision of fuel-air charge preparing and introducing means which requires no skilled operator.

Another object is the provision of manually operable means for rendering the fuel-air charge preparing device inoperative as soon as the pulse jet type space heater is set into operation by explosion of the fuel charge.

Another object of the invention is the provision of means for preventing operation of the air inlet means for the fuel-air charge preparing device while the spot heating device previously mentioned is manually set into operation.

Referring now to the accompanying drawings: Fig. 1 is a side elevation, partly in section.

Fig. 2 is a fragmentary plan view of the valve plate of the pulse jet heater.

Fig. 3 is a section of the valve plate taken on the line 3—3 of Fig. 2.

In Fig. 1, 10 is a combustion chamber of generally pear-shape, which has an outlet tube 11 for the discharge of combustion generated therein, and forming with chamber 10 the pulse jet combustion resonator, the tube 11 entering the mouth of a flared end air delivery tube 12 which may be of the plain air aspirator and fuel mixing

2

type or of the resonator type as described in the copending application of W. I. E. Kamm et al., Serial No. 129,861—Patent 2,643,107 dated June 23, 1953.

The combustion chamber 10 is provided with a carburetor 13 having a suitable air inlet (not shown) and a fuel pipe 14 leading from the fuel tank (not shown). The ratio of fuel to air in the mixture prepared by the carburetor 13 may be regulated by an adjustment member 15. Immediately above the carburetor 13 there is a perforated valve plate 16 which may be of the type shown in Figs. 2 and 3. It consists in general of an upper multiperforated plate 9 and a lower multiperforated plate 8 having registering openings in which hemispherical valve means 5 are displaced upwardly from the perforations in plate 8 and through the separating space 7 created by the presence of a ring 6. The upward rush of the fuel-air charge prepared in the carburetor 13 into the combustion chamber 10 occurs by reason of the resonant effects of the shock wave generated in the combustion chamber, the shock wave being reflected at the open end of tube 11 as a low pressure wave. The operation of such resonant shock waves is well understood in regard to their action in pulse jet motors. The hemispherical valve means 5 act to seat in and close the perforations in the plate 8 upon being subjected to an oppositely acting force and explosion in the combustion chamber 10.

The mechanism designed to preheat a spot indicated at 17 on the wall of the combustion chamber comprises an outlet pipe or horn 18 which for intensifying the flame may here be provided with a multiplicity of air inlet ports 19 near its outer end 20, which is preferably flared. The pipe 18 is set in a liquid tight manner by means of a diaphragm 21 forming the bottom of a fuel boiler or fuel heating and vapor pressurizing chamber 22. The boiler 22 is provided with a filler pipe and cap 23 through which it may be filled preferably nearly up to the top with liquid fuel 25, which may be gasoline. A space 24 above the fuel is intended to contain vaporized fuel provided by heating the body of the fuel 25 by means of a burner 27 of the type which has a needle valve 28 and which is arranged coaxially with and below the pipe 18. A layer of incombustible fibrous material 29 is provided at the bottom of the lower chamber 30 of the fuel vaporizing boiler 22, the chamber being provided with air inlet openings 22a above the layer 29. This fibrous material, which may be as-

bestos, is saturated with fuel by means of a fuel inlet pipe 34 which may derive fuel from the same tank from which pipe 14 is also supplied.

Communication between the space 24 of the boiler 22 and the space 34 within burner 27 is provided by a vapor delivery and superheater pipe 32 which is coiled about the lower end of the outlet pipe 18 within the chamber 24. The upper end of the pipe 32 is open above the liquid in the boiler, whereby to receive under pressure the vaporized fuel held in the space 24 and to deliver it through the diaphragm seal or bottom 21 to a fuel duct 33 which communicates with the annular fuel space 34 which surrounds the needle 28 of the burner 27. From the junction point 35 of the pipe 32 with the fuel duct 33, vaporized fuel is then able to flow in two directions, i. e., through the annular space 34 on the one hand to the burner 27 and on the other hand to an operating space or valve chamber 36 contained in a valve housing 31. In an outlet from the space 36 a valve 38 of the poppet type is seated, normally to seal off, under the urging of spring 39, a vaporized fuel delivery pipe 40 which extends to a starting-charge forming or mixing device 41, which is preferably located on that side of the combustion chamber 18 which is substantially opposite to the spot 17 which is to be heated. Such location allows a short length of tube 40 to be used, whereby to avoid heat losses and to provide for directing the starting fuel-air charge with certainty toward the hot spot 17 on the interior wall of the chamber 18.

Actuation of the valve 38 is provided for by a rod 42 to which the poppet valve 38 is coaxially connected. The rod 42 is provided with a flange 43 for tensioning the coil spring 39 against the valve housing 31. The rod 42 is slidably in a bearing 44 by means of a lug 45 which is attached to the rod and to the short arm of a bell crank 46. Upon the upper surface of the long arm of the bell crank 46 there is a boss 47 which is arranged to make contact with a striker plate 48 located on the bottom of a carrier 49 of a ring-type air valve 50 which is adapted to seat against a bottom surface of an annularly slotted cover 51 of a bowl or body 52 of the air valve 41 and close the air inlet openings therein. The pipe 40 connects into the bowl or body 52 through its bottom, preferably below the center of the ring air valve 50 and its end is directed as a jet nozzle into the mouth 53a of pipe 53. The starting charge inlet pipe 53 connects the covered, annularly slotted cover of the bowl 52 at its center with the interior of the combustion chamber 18, so located relative to the spot 17, that the fuel-air charge delivered by pipe 53 into the combustion chamber reaches the hot spot 17.

A manual starting means for the charge forming device 41 is provided in the form of a push button 54 which is normally urged upwardly by the pressure of the coil spring 55 above a support 56 which is preferably on a higher level than the charge forming device 41. The button 54 is connected by a rod 57 with a long arm of a bell crank 46 which in turn is pivoted on a rigid support 58 at 59. The shorter arm of the bell crank 46 is connected to the lug 45.

To set the device in operation, the pad or liner 29 of porous material is first moistened with fuel from the pipe 34 after which the supply of fuel thereto is turned off. The chamber 25 is filled approximately full of fuel leaving the space 24 above the fuel level. This chamber may be filled through the filler pipe 23. A lighted match

is then applied to the saturated porous material 29 through one of the openings 22a in the lower part or chamber 30 of the boiler 22. The flame from the ignited fuel in the wick 29 heats up the fuel 25, vaporizes it and pressurizes boiler 22. The needle 28 is then opened and the flame fed by burner 27 and by air admitted through the openings 22a, now ascends the pipe or horn 18, sucking in additional air for combustion through the holes 19. The essentials of retort combustion are thereby accomplished and a flame hot enough to heat the spot 17 to incandescence is soon produced. The pressure inside the space 24 is checked by means of gauge 58 and the needle valve 28 may be adjusted accordingly. However, the combustion does not become too violent to cause rupture of the container 22 from excessive internal pressure because the strength of the boiler 22 and the lower part of tube 18 is dimensioned for safely holding the highest pressure which is permitted by the rate of gas outflow at burner 27.

During this time, the poppet valve 38 has remained closed under the urging of the spring 39. When the spot 17 on the combustion chamber wall has become hot enough to ignite a fuel-air charge in the combustion chamber 18, the push button 54 is manually depressed against the resistance of the spring 55 until the support 56 is encountered. The rod 57 depresses the longer arm of the bell crank 46, thereby causing the shorter arm to move the lug 45 and consequently the rod 42 to the right, thereby overcoming the resistance of the coil spring 39 and opening the poppet valve 38. Part of the vaporized fuel descending the vapor delivery and superheater pipe 32 now enters the fuel and air duct 33 and the operating space 36, ascending pipe 40 into the charge forming device 41. The ring valve 50 in the charge forming device 41 is now open due to the action of gravity, since the lug 47 on the arm of the bell crank 46 has been lowered, permitting the carrier 49 to drop with it. Such action unseats the ring valve 50 from the circular air inlet slot or seat 51, thereby allowing air to enter and mix with the vaporized fuel projected into pipe 53 from the vaporized fuel supply pipe 40. An aspirating action is produced by the spray of fuel to the pipe 53, thereby entraining air. The button 54 must be held depressed manually during this time until the charge within the combustion chamber 18 becomes ignited by contact with the hot spot 17. An explosion then ensues, which closes the openings in the valve plate 16, back pressure in starter pipe 53 also tending to close ring air valve 50. More explosions follow, alternately closing and opening ring air valve 50. However, after the first explosion, it is unnecessary to hold the button 54 depressed, so it should be released at this time, the resonant action of the pulse jet motor being able to continue by drawing fuel and air through the carburetor 13 into the interior of the combustion chamber 18. The charge is exhausted after explosion through the exhaust pipe 11. After the button 54 is released, the poppet valve 38 again closes under urging of the spring 39; the button 54 is raised under the urging of the spring 55 and the annular valve 50 positively is closed by the upward push given to the carrier 49 against the striker plate 48 by the boss 47 on the bell crank 46. The flame or pressure which may descend the charge inlet pipe 53 into the charge forming device 41 has the effect of making the seal between the annular air valve 50 and its

seat 51 tighter on account of upward fluid pressure. It will be seen therefore that the starting mechanism which is the subject matter of our invention, is entirely idle during the operation of the pulse jet heater.

Combustion engineers in possession of this disclosure will be able to make changes and adaptations which will fit our starting device for operation with various kinds of heaters. The invention is therefore not to be limited except by the scope of the appended claims.

What we claim is:

1. A starting device for a pulse jet type space heater having a combustion chamber and a discharge pipe extending therefrom, comprising a fuel heating vaporizing and pressurizing chamber adapted to have a quantity of liquid fuel introduced therein, an upwardly directed central combustion pipe extending through said fuel vaporizing and pressurizing chamber having a heat outlet at its upper end for directing flame and combustion gases to a spot on the exterior of the pulse jet combustion chamber to heat the spot thereon for the ignition of an explosive fuel charge when introduced into the pulse jet combustion chamber against said heated spot, a vaporized fuel jet burner positioned concentrically at the lower and inlet end of said combustion pipe, a fuel heating casing surrounding the mouth of said combustion pipe and said burner having air admission ports formed therein, a wick of non-combustible fibrous material positioned in the fuel heating casing surrounding the burner below the air admission ports, a vaporized fuel superheating and vapor delivery pipe surrounding the combustion pipe within the fuel heating vaporizing and pressurizing chamber with its upper end in communication with the interior of the last mentioned chamber adjacent the top thereof above the normal liquid level of the fuel to be introduced in said last chamber, a vaporized fuel delivery duct connected intermediate its ends to the other end of said superheating and vapor delivery pipe, said fuel delivery duct being connected at one end to said burner, a needle valve for said burner, a charge forming device having a fuel and air mixing chamber and a fuel and air mixture discharge pipe adapted to be connected in communication with the interior of the pulse jet combustion chamber at the side thereof opposite said spot for directing a vaporized fuel and air mixture into the pulse jet combustion chamber toward the heated spot, vaporized fuel injection means positioned in said mixing chamber below said fuel and air mixture discharge pipe and connected to the other end of the fuel delivery duct for injecting vaporized fuel from the fuel heating, vaporizing and pressurizing chamber through the said fuel and air mixing chamber into the fuel and air mixture discharge pipe, poppet valve means in said fuel delivery duct intermediate the vapor delivery pipe connection to said duct and said vaporized fuel injection means, means normally urging said valve means to closed position, manual valve opening means including rod linkage, bell crank lever, and spring opposed means operatively connected thereto for opening said valve means, air inlet valve means in said fuel and air mixing chamber movable to admit air into the fuel and air mixing chamber, and means carried by the valve opening means for closing the air inlet valve means to cut off air supply to the fuel and air mixing chamber simultaneously with the closing of the valve 75

means for controlling the supply of vaporized fuel from the fuel heating, vaporizing and pressurizing chamber upon release of the poppet valve opening means.

5 2. A space heater of the pulse jet type comprising a wall forming a combustion chamber in the shape of a domed inverted cone, an exhaust pipe therefrom, a retort type of spot heater at one side of said combustion chamber adapted to heat a spot on the exterior wall of said chamber about midway up the wall to incandescence, a starting charge injection pipe in fluid communication with the interior of said combustion chamber substantially opposite to the spot to be heated, a fuel and air mixture intake valve plate below the combustion chamber, a carburetor below said valve plate for supplying an explosive fuel-air mixture into said combustion chamber, conduit means for supplying fuel to said carburetor, 10 said spot heater including a fuel heating and vaporizing means and a vaporized fuel burner therefor, conduit means from said fuel heating and vaporizing means connected to said burner to deliver vaporized liquid fuel for said spot heater, a fuel and air charge forming device, quick acting vaporized fuel valve means in said conduit means controlling delivery of fuel to said fuel and air charge forming device, spring means normally holding said vaporized fuel valve 15 closed, an air inlet valve in said charge forming device adapted to open under the action of gravity to admit air into said fuel and air charge forming device, and manually actuatable means adapted to open said vaporized fuel valve and to simultaneously release said air inlet valve whereby to allow it to open, said manually actuatable means including a spring therefor which must be compressed to open the vaporized fuel and air inlet valve and which will, upon cessation of 20 manual effort, return said vaporized fuel and air inlet valve to its closed position whereby to seal said charge forming device and cause said combustion chamber to initiate its cycle by drawing into the combustion chamber through said valve 25 plate a fuel-air mixture prepared in said carburetor.

3. In combination, a space heater comprising a wall forming a combustion chamber, an exhaust pipe therefrom, a carburetor for supplying a combustible fuel and air mixture into said combustion chamber, a check valve plate between the carburetor and the said chamber, and a starting device for introducing a fuel and air explosive charge into the combustion chamber 30 and for heating said wall to initiate combustion of said explosive charge in said chamber, said starting device comprising a heater for vaporizing fuel and for heating a spot on the exterior of said wall for the ignition of an explosive fuel-air charge when directed into the combustion chamber against the heated spot, said heater comprising a burner including a combustion tube therefrom having a discharge end facing toward said spot for directing flame and combustion 35 gases against said spot, a fuel vaporizing chamber heated by said burner to vaporize the fuel therein, and a fuel supply pipe connecting said fuel vaporizing chamber to said burner, a fuel-air charge forming device including means for introducing air therein, a fuel and air charge injection tube connecting the charge forming device and the combustion chamber and arranged to direct said fuel-air charge into said combustion chamber and against the surface of said 40

45

50

55
